UNITED STATES PATENT OFFICE.

WILLIAM LUND, OF CATHLAMET, AND WILLIAM B. LLOYD, OF SKAMOKAWA,
WASHINGTON,

STEERING GEAR.

1,080,766.

Specification of Letters Patent. Patented Dec. 9, 1913.

Application filed February 11, 1913. Serial No. 747,826.

To all whom it may concern:

Be it known that we, WILLIAM LUND and WILLIAM B. LLOYD, citizens of the United States, residing at Cathlamet and Skamokawa, respectively, in the county of Wahkiakum, State of Washington have invented a new and useful Steering-Gear, of which the following is a specification.

The present invention relates to an improvement in steering gears, the primary object of the invention being the provision of means whereby the slack in the steering cable may be easily adjusted and taken care of without the necessity of releasing the respective ends of the cable, such slack being removed where the coils thereof pass about the steering spool or drum.

A further object of the present invention is the provision of a sectional steering drum, in which the sections are detachably connected together, whereby the same may be detached and rotated independently to increase the number of coils thereupon and thus adjust the steering cable to the desired tautness.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings:—Figure 1 is a longitudinal sectional view through the sectional steering drum with parts in interlocked position. Fig. 2 is an end view of the inner drum taken from the locking side thereof. Figs. 3 and 4 are detail end views of the outer drum. Fig. 5 is a plan view taken from the inner face of the steering wheel.

Referring to the drawings, the numeral 1 designates a spindle which is fixedly mounted and has secured upon its outer screw-threaded end the lock nut 3, which maintains the steering wheel 4 against outward displacement yet permits the rotation thereof upon the spindle 1, said steering wheel being provided with a plurality of inwardly projecting pins 5, which are disposed to fit within the sockets 6 in the outer face of the outer steering drum or spool 7,

thus the spool 7 is held interlocked for rotation with the steering wheel 4.

The inner face of the spool 7 is provided with the radiating slots 8, which are disposed to receive the radiating lugs or projections 9 of the inner drum or spool 10, the opposite end of the spool 10 being provided with the concentric socket 11 for the reception of the spring 12, which is disposed upon the spindle 1 adjacent the socket 11 and has its opposite end fitted within the socket 13 of the securing bracket which properly supports the steering mechanism, as clearly shown in Fig. 1. It will thus be seen that the coils 14 of the steering cable are wound upon the respective spools 7 and 10, and that by reason of the spring 12 and interlocking means 8 and 9, and 4 and 6, these spools or drums are connected to be rotated through the medium of the steering wheel 4.

Should the coils 14 be slackened due to the stretching of the rope, the section 10 is moved toward and against the tension of the spring 12, until the ribs or lugs 9 are moved from the sockets 8 of the spool 7, at which time the spool 10 is rotated in the desired direction to place thereupon the necessary amount of the cable to produce the desired tautness therein, or if desired the spool 7 may be rotated in an opposite direction from the spool 10, thereupon placing the slack of the cable evenly upon the respective spools 7 and 10. After the cable has been tightened, the spool 10 is released and the spring 12 will maintain both spools interlocked.

From the foregoing description, it is evident that with a steering gear constructed according to the present invention, that the wheel 4 through the medium of the interlocking means 5 and 6, and 8 and 9, and the spring 12, produces the desired method of rotation in spools 7 and 10, and that by reason of the said connection, the spools may be separated and adjusted to remove the slack from the cable, without the necessity of detaching the ends of the cable from the rudder post or rudder gear, thus placing at the command of the pilot the adjustment of the cable and dispensing with the tedious and trying operations necessary to usually tighten the same, especially where such cables are through intricate passageways from the steering wheel to the rudder.

It is also evident by the simple removal

of the cap nut 3 that the various parts of the steering device may be removed from the spindle 1, for renewal or repair and without to any great extent interfering with 5 the coiling of the cable upon the spool.

What is claimed is:—

1. A steering gear including a spindle, a socketed support for one end of the spindle, a wheel mounted upon the spindle for rotation, two detachable and interlocking spools detachably connected to the wheel, the inner end of the inner spool being disposed to move into and out of the socket of the support, and a spring disposed within the socket 10 of the support about the spindle and abutting the inner spool for holding the spools interlocked and whereby the sections may be disconnected and the spools rotated independently to remove the slack in the steering 15 cable.

2. A steering gear, including a stationary socketed base, a fixed spindle, having one end secured in the base, a wheel controlled

25 spool rotatably mounted on the spindle, a second spool slidably and rotatably mounted on the spindle, the face of the first spool adjacent the second spool being provided with radial slots, a plurality of radial ribs carried by the second spool for engagement with the slots of the first spool to lock the 30 spools for movement in unison, and a spring mounted within the socket of the base and upon the spindle and exerting a pressure upon the second spool to maintain the spools interlocked and to permit the inner spool 35 to be moved longitudinally to separate the spools for independent rotation.

In testimony that we claim the foregoing as our own, we have hereto affixed our signatures in the presence of two witnesses.

WILLIAM LUND.

WILLIAM B. LLOYD.
